MAGNETIC RECORDING APPARATUS

James W. Bryce, Glen Ridge, N. J., assignor to International Business Machines Corporation, New York, N. Y., a corporation of New York

Application November 29, 1941, Serial No. 421,079

4 Claims. (Cl. 234—1.5)

This invention relates to magnetic recording apparatus, and particularly to such apparatus wherein discrete magnetic impressions or representations are recorded, on a magnetizable sheet, at different code or index point positions for representing the data desired to be recorded.

An object of the present invention resides in the provision of an improved and simplified apparatus for recording discrete magnetic data representations.

To this end, a keyboard control unit and a recording unit are provided, wherein a plurality of instrumentalities are selectively manipulated, at will, in the keyboard unit, in accordance with the data to be recorded, for controlling differentially settable devices, which devices, in turn, cause individual printing means and magnet selector means to be set at different positions for representing the data. Suitable means are provided for rendering the printing means operative to print the data at predetermined line spaces on the magnetizable sheet. Intermittently operable sheet feeding means are provided and called into action to present the sheet to the magnetic recording station upon completion of the printing operation. A plurality of groups of recording magnets are provided at the recording station which are supported by cyclically operable positionable means for placing the said magnets in a recording or non-recording position. Sheet feeding operations are effected while the magnets are in a non-recording position. In the recording position, the magnetizable sheet is wedged between the magnet pole-pieces and a backing plate member of suitable magnetic material. The magnets are selectively connected in control circuits by the differentially settable magnet selector means, so that individual capacitor means are effective upon their discharge to energize the selected magnets of each related group, and thereby effect recording of discrete magnetic representations at predetermined code positions on the magnetizable sheet. Switching means are provided, which are operated in timed relationship with the printing means, the sheet feeding means, and the magnet positioning means, for alternately connecting the individual capacitor means to individual charging and discharging circuits, the latter circuits including the selected recording magnets, so that the selected recording magnets of each group are energized upon the discharge of the related capacitor means.

Accordingly, another object of the present invention resides in the provision of cyclically operable means for automatically effecting the alternate connection of capacitor means, such as a condenser, to a related charging and discharging circuit, whereby one or more selected magnets of a group are energized, by the discharge of said capacitor means, for effecting the recording of

one or more coded discrete magnetic impressions or representations on a magnetizable sheet.

Another object of the present invention resides in the provision of cyclically operable means for placing a group of recording magnets in recording and non-recording positions, the operation of which is under control of the will of the operator.

Another object of the present invention resides in the provision of an improved magnetic recording apparatus wherein the magnetizable sheet is wedged between the pole-pieces of a group of magnets and a backing plate member of suitable magnetic material, whenever the said magnets are placed in a recording position.

Another object of the present invention resides in the provision of an improved magnetic recording apparatus wherein intermittently operable sheet feeding means are provided for advancing the said sheet only at such times when the group of magnets are in a non-recording position.

Still another object of the present invention resides in the provision of means operated in timed relationship with the magnet positioning means for effecting the discharging of the said condensers only at the times when the recording magnets are in a recording position.

Still another object of the present invention resides in the provision of an improved recording unit wherein a plurality of recording magnets are retained in spaced relationship in a common member of magnetic material.

Still another object of the present invention resides in the provision of an improved recording unit wherein a common backing plate member of magnetic material is positioned opposite the group of spaced recording magnets in order to concentrate the flux in separate perpendicular paths in the magnetizable sheet.

Still another object resides in the provision of an improved magnetic recording apparatus wherein the data is printed on predetermined line spaces on the sheet at one station, and recorded magnetically at predetermined areas on the sheet at another station, whereby each area containing the magnetic representations bears a fixed linear relationship to the related area or line space in which the printed data is formed.

Other objects of the invention will be pointed out in the following description and claims and illustrated in the accompanying drawings, which disclose, by way of example, the principle of the invention and the best mode, which has been contemplated, of applying that principle.

55 In the drawings:

Keyboard control unit

Referring now to Figs. 1 and 2, the keyboard control unit, generally designated by the reference character A, will be described briefly. It will be understood, as the description progresses, that the purpose of this unit is merely to provide manipulative instrumentalities, such as keys 20, for effecting the selection of predetermined control elements in the magnetic recording unit, in accordance with the selected keys. For illustrative purposes, a specific and well known type of keyboard control unit, which is called into operation at will, is shown for exercising the desired selective control over the said recording unit. Obviously, other types of manipulative control units can be used to effect such selective control, therefore, due to the fact that a keyboard control unit of the cash register type is employed in the present embodiment, it is not to be construed that the present invention is limited solely to be controlled by such mechanism.

The construction and operation of the illustrated keyboard control unit is well known, and as mentioned is of the cash register type, therefore, the brief general description to be given now is believed sufficient for complete comprehension of the present invention. The structure of this keyboard control unit is similar to the structure shown and described in U. S. Patent No. 1,816,263, dated July 28, 1931, thus, for a complete and detailed description of the mechanism of the present keyboard control unit, reference should be made to this last mentioned patent.

A plurality of similarly constructed banks of keys are provided, three banks of amount designation keys, and one bank of classification designation keys. The keys 20 comprising each bank are slidably mounted in separate key frames 21, which are arranged side by side and suitably supported in the unit. Springs 22 return the keys to, and hold them in, their undepressed positions. Provision is made in cash registers of this type, whereby upon depression of a key 20 and the motor bar 23, each selected key is locked in the depressed position, during the operation of the unit, and near the end of the operation of the unit, the selected keys are released and restored to the normal undepressed positions.

Each depression of the said motor bar causes the motor driven cam shaft 24 to be driven through one complete rotation by a train of well known mechanism, which is described in detail in the said Patent No. 1,816,263. Upon rotation of the said cam shaft 24, a restraining and restoring bar 25 is rocked first in a clockwise direction, and then a counterclockwise direction. During the rocking of the said bar 25 in the clockwise direction, an actuator 26 is permitted to be rocked, under the influence of a spring 27, until stopped by the end of a depressed key 20, or by a zero stop pawl, in the event no key in a bank is depressed. After the actuator 26 has been positioned under control of one of the keys 20, the said actuator and bar 25 are restored to their home positions.

Pivoted on the cross shaft or rod 28, adjacent each of the segmental actuators 26, is a companion segment 29 provided with teeth 30 identical and concentric with the teeth 31 of each related actuator 26. Each indicator segment 29 is also provided with teeth 32, which mesh with a related gear 33. Each of the gears 33 provided is secured to one end of a cross shaft 34 or one of the nested sleeves 35 surrounding the said cross shaft 34. Each gear 33 also meshes with a related gear 36, which gear 36 meshes with the related pinion 37 secured to a corresponding indicator wheel 38.

The mechanism provided in the present keyboard control unit for adjusting the indicator wheels 38 is of the type in which the indicators are always first brought to zero, and then adjusted to their new positions under control of the provided differential mechanism.

Each indicator segment 29 is provided with an abutting face 40, so, as the restraining and restoring bar 25 is rocked, in a clockwise direction, it contacts the abutting faces 40 of such of the indicator segments 29, as may stand in other than their home positions, to restore them and all of the corresponding indicators 38 to their zero positions.

It will be remembered that during the forward movement of the restraining and restoring bar 25, the adjacent actuators 26 are under control of the depressed keys 20. After all of the indicator segments 29 have been set to their zero positions, and the actuators 26 are adjusted, common control pinions (not shown) are adapted to engage the teeth 30 and 31 of the segments 29 and actuators 26, respectively. After this engagement, the restraining and restoring bar 25 is returned to its home position, thereby returning all of the actuators 26 to their home positions. Since the related actuators 26 and segments 29 are now engaged with a common control pinion, it is apparent that the segments 29 are positioned differentially to adjust the related indicators 38, by means of gears 33 and 36, to different positions to indicate the selected amount represented by the depressed keys 20.

Thus, it is seen, upon operation of the manipulative instrumentalities, by depressing the selected keys 20 and the motor bar 23 (or if desired by turning the crank 41 instead of calling in the said motor bar), the cam shaft 24 is rotated one revolution to set or adjust the corresponding indicator wheels 38 from their home or zero positions to different positions to indicate the amount or data represented by the selected and depressed keys. It should be remembered too that each corresponding gear 36 is also differen-

tially positioned to control the positioning of the related indicator. It should be mentioned, also, that secured to the said cam shaft 24 is a gear 42 which meshes with an idler gear 43, both of which are set into operation, upon rotation of the cam shaft. The purpose of this drive will be explained presently, in conjunction with the description of the recording unit.

Recording unit

The recording unit, generally designated by the reference character B (Figs. 1-3) is arranged as a distinctly separate and detachable unit from the keyboard control unit A. Certain control elements, which will be described later, of the recording unit are adapted to engage the differentially positioned gears 36 and the idler gear 43 of the keyboard control unit A, when the said recording unit B is attached to the said unit A.

The recording unit B comprises, generally, two sections, namely, the magnetic data recording section, and the data printing section. By means of the magnetic recording section, the selected data, represented by the depressed keys 20, are recorded magnetically upon a strip or sheet of magnetizable material. The magnetic representations or impressions representing the selected data are discrete magnetic impressions formed on the magnetizable record sheet at predetermined code or index point positions. These coded magnetic impressions will be referred to as discrete magnetic index points to distinguish from the well known form of sound tracks represented by the continuous magnetic impressions recorded on suitable magnetizable materials.

In addition to recording magnetically the selected data, this data is also printed on the magnetizable record sheet by means of the said printing section. It will be seen that the printed data is disposed so as to bear a fixed linear relationship with the magnetic index points representing the data and corresponding to the said printed data. It has been found by experiment that this provision is a necessary one, because in the machines adapted to be controlled by the magnetized sheets or strips formed by the present invention, it is important that certain indicating marks, such as the printed data, be provided, in order to assure that the magnetized sheets are properly positioned, in the machines to be controlled thereby, with respect to a fixed reference point in the controlled machine. Therefore, in addition to interpreting the magnetic index points, the printed data become fixed indicating marks, which bear a fixed linear relationship to the magnetic data index points, whereby it can be determined whether or not the said magnetized sheets are properly positioned in the machines controlled by such sheets or strips. A controlled machine of this character is described and claimed in Patent 2,302,002, issued November 17, 1942.

Magnetizable record sheet.—Referring now to Figs. 13-15, a suitable magnetizable record sheet or strip 50 is shown to comprise a paper carrier or base 51 which is coated with magnetizable granular material 52, and a layer of paper 53 suitable for receiving printed impressions covering the said magnetizable material. To this end, suitable metal powder or filings may be suspended or mixed in any suitable binder and sprayed or coated on one of the plies or layers of paper. This binder may contain suitable adhesive material in order to bond securely the magnetizable material to both plies of paper, and

thus form a unitary structure of the three layers of material. If preferred, other types of magnetizable record material can be used, for example, one of the types shown in Figs. 4 to 9 of U.S. Patent No. 2,254,931.

In Fig. 13, a fragmentary section of the continuous record sheet 50 is shown and comprises individual records formed thereon at equally spaced intervals, which are indicated by the reference characters a—c. Each individual record comprises a line of printed data, as indicated by the reference character 54, which printed data correspond to the magnetically recorded data, and a plurality of discrete magnetic index points, indicated by the reference character 55. Obviously, the magnetic impressions on the record sheet are not visually discernible, but are merely indicated, by the shaded areas 55, to show the code positions of certain of the data representing magnetic impressions. The combinational code employed to represent various data is shown in Fig. 14. The code or index point positions for the available columns on the record sheet are shown by the cross marks in the first individual record a on the sheet. It is to be noted that the printed data 54 of each record is disposed at a predetermined and fixed location on each record, and that the magnetic index points are disposed in a predetermined and fixed area on each record. The linear relationship between the line of printed data 54 and the magnetic index points 55 is a fixed relationship, which arrangement will be described in more detail hereinafter. It should be mentioned too, that the usual marginal or feed perforations 56 are provided in the instant record sheet 50.

Record feeding means.—Referring now to Figs. 2-4, and 8, it is seen that the record sheet 50 is fed from a supply roll 60 over the idler rollers 61, past the printing station generally designated 62, the magnetic recording station generally designated 63, idler roller 64, sprocket feed roller 65 to the take-up roll 66. The record sheet is fed, once each cycle, near the end of each cycle, as indicated in the timing chart (Fig. 12). This feeding operation occurs between the printing operation and the magnetic recording operation, the purpose of which will become apparent. The mechanism for effecting the intermittent record sheet feeding operations will now be described.

The idler gear 43, which is driven by gear 42 on the cam shaft 24, meshes with a gear 67 secured to the main shaft 68 of the recording unit, and suitably supported therein by the side plates 69. Also, secured to the said main shaft 68 is a mutilated driving gear 69, the teeth 70 of which, engage, during the rotation of shafts 24 and 68, the teeth 71 of the mutilated gear 72, thereby effecting a partial rotation of gear 72, for each revolution of gear 69. The said mutilated gear 72 is secured to the sprocket feed roller 65, which roller 65 in turn is rotatably mounted on a stud shaft 73 suitably supported by the intermediate plate 74. The teeth 70 and 71 of gears 69 and 72, respectively, are arranged so that, for each partial rotation or intermittent movement of gear 72 and feed roller 65, the record sheet 50 is advanced a predetermined distance D, as indicated in Fig. 13.

An expedient friction drive for the take-up roll 66 is provided, and comprises a gear 75 also secured to gear 72 which meshes with an idler gear 76 rotatably supported by the arm 77 which gear 76 in turn meshes with gear 78 rotatably mounted on a stud shaft 79 carried by the said

arm 77. Secured to gear 78 is a roller 80 provided with suitable friction rolls 81. The arm 77 is pivotally supported by the stud shaft 73 and by means of spring 82 is urged in a counter-clockwise direction (as viewed in Fig. 4) so that the driven friction rolls 81 always engage and effect positioning of the take-up roll 66, during the intermittent record feed operations.

Magnetic recording means.—Referring now to Figs. 3, 4, 8 and 10, the means for effecting the magnetic recording of the selected data on the magnetizable sheet 50 at the generally designated magnetic recording station 63 will now be described.

A plurality of individual recording magnets 85 are provided, each of which has a slightly protruding pole-piece 86, which pole-pieces are rectangularly shaped as shown in Fig. 8. These recording magnets are supported by a common retaining block 87 of suitable magnetic material, such as soft iron, which block 87 is provided with a plurality of spaced apertures 88 for receiving and retaining the individual magnets. A plurality of vertically arranged columns or rows of apertures 88 are provided, each column or row having, in the instant case, four equally spaced apertures. The individual magnets 85 retained by a column or row of four apertures (see Fig. 8) will be referred to as a group of recording magnets. The arrangement of the said apertures is such that each magnet of a group is spaced vertically so as to correspond to the vertically spaced index point positions of a column indicated in Fig. 13, and the individual groups of magnets of each column are spaced horizontally to correspond to the individual columns of index point positions indicated in Fig. 13.

The retaining block 87 is mounted on a member 89 constructed of suitable electrical insulating material, which member in turn is secured to one arm of a bell crank lever 90. The said lever 90 is rotatably mounted on a sleeve 91 supported by the cross shaft or rod 92. The other arm of bell crank lever 90 is pivotally connected to one end of a cam follower arm 93, the other end of which is bifurcated to partially surround the shaft 68. A cam roller 94 is suitably disposed on the said follower arm 93, which cam roller 94 rides on the periphery of the cam element 95, the latter being secured to shaft 68.

The normal or home position of the mechanism just described is shown in Figs. 3 and 4, whereby the said retaining block 87 and the groups of magnets 85 supported thereby are maintained in a position so that the pole-pieces 86 of the magnets 85 are held away from the magnetizable record sheet 50. This position of the groups of recording magnets 85 will be referred to as a non-recording position.

Now, upon rotation of the shaft 68, the cam element 95, near the end of each cycle of rotation of shaft 68, causes the cam follower arm 93 to be raised to its uppermost position and thereby cause the retaining block 87 and the groups of magnets, supported by the bell crank lever 90, to be partially rotated in a clockwise direction. Due to this operation, the magnets are positioned in what will be termed hereinafter as the recording position, i. e., the magnets are positioned, as shown in Fig. 10, so that the pole-pieces 86 of the magnets 85 contact the magnetizable record sheet 50 at the index point positions of the individual records as indicated in Fig. 13.

At the said recording station 63, the magnetizable record sheet 50 rests against a backing plate

or block 96 of suitable magnetic material, such as soft iron, which is supported by one of the side plates 49 and the intermediate plate 74. The said backing plate member 96 is arranged to extend beyond the area, both vertically and horizontally, to be recorded on the said magnetizable record sheet. Thus, it is seen, particularly in Fig. 10, that when the groups of magnets 85 are positioned in the recording position, the pole-pieces 86 thereof not only are placed in intimate contact with the magnetizable sheet 50 but actually wedge the magnetizable sheet between the said pole-pieces and backing plate member.

When the said magnets 85 are positioned in the described recording position, means to be described later herein are effective to select certain magnets of each group and connect these selected magnets to circuit energizing means to energize the selected magnets, and thus cause discrete magnetic impressions to be recorded in the code or index point positions on the magnetizable sheet in accordance with the selected data set up on the keys of the keyboard control unit. It has been determined, by experiment, that, by using a backing plate of highly permeable material having low retentivity characteristics, on the side of the highly retentive record sheet opposite the magnet pole-pieces, greater concentration of the magnetic field or flux, in a path perpendicular to the surface of the record sheet is obtained. It is to be noted that not only is the surface of the backing plate against the record sheet greater in area than the area to be recorded on the record sheet, but also that the thickness of the backing plate is substantially the same as the length of the entire pole-piece of each magnet. For static recording of the type described herein, that is, the type of magnetic recording on record sheets wherein the latter are held stationary during the recording operation, and wherein discrete magnetic impressions are formed, it has been found desirable to employ backing plates of relatively greater thickness in order to prevent spreading of the flux between the designated index point positions.

Recording magnet selector means.—Referring now to Figs. 5, 6, 8 and 9, the individual means for effecting the selection of certain magnets of each group will be explained. Each of the said individual means comprises an arcuate bank of fixed contacts 100, which contacts are disposed, at equally spaced positions, in an electrically insulating segmental member 101. In addition thereto, each segmental member 101 is provided with a common elongated contact member 102. An individual bank of contacts 100 and 102 is provided for each column of data to be recorded on the magnetizable sheet, or stated in other words, a bank of the said contacts is provided for each vertically arranged group of magnets 85. The individual segmental members carrying the said contacts are held in a suitably spaced relationship by the individual spacing blocks 103, which assembly is suitably secured to one of the side plates 49.

Individual sets of spaced conducting means 104 are provided for each arcuate bank of contacts 100 and 102. Each set, in the instant case, consists of six radial conducting arms 105 which form an integral part of the common arcuate conducting segment 106, which arms are arranged to engage and connect predetermined ones of the contacts 100 to the common elongated contact 102 depending upon the settings of each of the set of conducting arms. In Fig. 9,

the different combinations of the connection of the contacts 100 to the common conducting contact 102 are shown for each setting of the rotatable conducting arms 105.

Each of the said common arcuate conducting segments 106 is fixed to an individual arcuate insulating strip 107, which in turn is secured to a suitable annular member 108. With reference now to Fig. 6, the individual annular members 108a-d are shown to be connected to individual actuating means which will now be described. Member 108a is secured to a sleeve 109a which sleeve in turn is fixed to a shaft 110 supported at its ends by the side plates 49. Also fixed to the shaft 110 is another sleeve 111 to which a segmental gear 112a is secured. Members 108b to 108d are secured to the ends of the nested sleeves 109b to 109d, respectively, which sleeves 109b-d surround the said shaft 110 and have secured thereto the segmental gears 112b, 112c, and 112d, respectively. Each of the said segmental gears 112a-d is arranged to mesh with a corresponding indicator drive gear 36.

It is remembered, upon operation of the keyboard control unit, that the positioning of the said gears 36 is under control of the selected and depressed keys 20, and that the gears 36 are differentially positioned in accordance with and corresponding to the selected keys. Since the segmental gears 112a-d are in constant mesh with the said gears 36, gears 112a-d, sleeves 109a-d and connected conducting arms 105 are differentially positioned or set in accordance with the settings of the gears 36. Thus, it is understood that various combinations of the contacts 100 of each bank are selected in accordance with the selected keys 20, which combinations of selected contacts are representative of the selected data. It will be described later herein, how the magnets 85 which are connected to the individual contacts 100, and selected by the described selector means, are energized to effect the recording of the magnetic index points representing the selected data.

Printing means.—Referring now to Figs. 4, 6 and 8, it is seen that individual type segments 115a to 115d are also secured to the differentially positioned sleeves 111, 109b, 109c, and 109d, respectively, so that the individual type elements 116, disposed on the said type segments, are selectively presented to the printing position, at the printing station 62, to permit printing of the selected data on the magnetizable sheet 50 in accordance with the selection of the data keys 20, whenever the said sleeves and related segmental gears 112a-d are operated. In view of the detailed description just set forth regarding the positioning of the said sleeves, further description regarding the positioning of the related type segments 115a-d is not deemed necessary.

In order to effect printing of the data upon the magnetizable sheet, the following means are provided. A print control cam element 115 is secured to the shaft 68 for cooperating with the cam follower arm 116 which is provided with a cam roller 117, the latter riding on the periphery of cam element 115. The cam follower arm 116 is bifurcated at one end and partially surrounds shaft 68, the other end of said arm being pivotally connected to an extension arm 118 of a bell crank lever 119 which lever is rotatably mounted on the cross rod 92. The depending arm 119 of lever 118 is provided with a camming surface 120 against a which a stud 121, fixed on an extension arm 122 of a lever 123, is urged by means of

spring 124. Lever 123 is pivotally mounted on cross rod 92 and at its upper extremity is provided with a transverse bail or hammer 125, which bail carries a suitable printing bar 126, which in the instant case consists of rubber material. The said bail and bar extend transversely across the faces of the type segments 115, so that the positioned type elements 116 are engaged thereby, at the printing station 62, when the said hammer arrangement is released to effect printing.

Now, upon rotation of the said shaft 68, the cam element 115, near the end of each cycle of rotation of shaft 68 (namely, the 265° point in the cycle, see Fig. 12), causes the cam follower arm 116 to be raised to its uppermost position, causing the print hammer arrangement to be in the maximum cocked position. The cam follower arm 116 is constantly urged in a downwardly direction, as viewed in Fig. 4, by the spring 127 secured to bell crank lever 118 and the intermediate frame 74. As the cam follower arm is raised by cam element 115, the depending arm 119 is partially rotated in a clockwise direction, thereby permitting the spring urged lever 123 and hammer arrangement including bail 125 and bar 126 to be partially rotated in a clockwise direction. At the 265° cycle point, the cam roller 117 drops from the high point of cam 115 to release the spring urged hammer arrangement, whereupon the bar 126, directed in a counterclockwise direction, is momentarily forced against the magnetizable sheet 50, which in turn is forced against the positioned type elements to effect printing of the data accordingly.

The usual inked ribbon medium 128 is provided between the type segments and the magnetizable sheet, which ribbon medium is advanced to and from the printing station by mechanism old and well known. A ribbon feed actuating mechanism 40 is provided, and briefly comprises a pivoted lever 129 (see Figs. 7 and 8) having a pair of spaced arms 130 and 131, which arms are provided with cam rollers 132 and 133, respectively. The said rollers 132 and 133 ride on the peripheries of complementary cam elements 134 and 135, respectively, the latter being fixed to shaft 68. The cam actuated lever 129 operates the pivoted link 136, which link in turn actuates the ribbon feed mechanism generally designated 137, at the times indicated in Fig. 12, during the rotation of shaft 68.

It was mentioned hereinbefore, that the magnetizable sheet 50 is fed one time each machine cycle, i. e. for each complete rotation of shaft 68. The record sheet feeding operation described 55 occurs after the printing operation and before the magnetic recording operation (see Fig. 12). The data set up in the differentially positioned type segments 115a-d are recorded at a predetermined position on each record, as indicated by the printed lines 54 on the individual records indicated by the reference characters a to c. Immediately after recording the selected data in the predetermined line space presented to the printing station 62, the sheet 50 is advanced, by the feed mechanism described herein, a fixed distance, indicated by the reference character D in Fig. 13. Thus, the next line space for receiving the printed data is presented to the said printing station, which printed data is recorded during the cycle following the just mentioned sheet feeding operation.

The predetermined area in which the magnetic index points are recorded is a fixed distance from the corresponding line of printed data. This area 75 is presented to the magnetic recording station

immediately after the printing operation, by virtue of the operated sheet feeding mechanism. The printing operation occurs at the 265° cycle point (see Fig. 12), and the sheet or record feeding operation occurs during the 270°-330° cycle points. The magnetic recording operation takes place shortly after the record sheet feeding operation, namely, approximately the 340° cycle point. The magnets 85 are held in the recording position from the 335° cycle point to the 345° cycle point. Individual switching means are provided for controlling the energization of the recording magnets at approximately the 340° cycle point, which will now be described.

Switching means.—Referring now to Figs. 5, 8 and 11, a plurality of individual switching means are provided, such as cam operated contacts 140a to 140d and 141a to 141d, the former being a group of normally closed contacts, and the latter a group of normally opened contacts. The contact assembly generally designated by the reference character 142, is suitably mounted on one of the side plates 49. The operations of each set of contacts of the mentioned groups are under control of a single and common cam element 143 which is secured to the shaft 68. The said cam element 143 is provided with a single notch or depression 144, which, during operation of the shaft 68, is effective at approximately the 338° to 342° cycle points to permit the pivoted follower arm 145 to be partially rotated in a clockwise direction, due to the action of the camming element 146 momentarily dropping into the said notch 144. Upon partial rotation of the follower arm 145, the group of normally closed contacts 140a-d are opened momentarily and the group of normally open contacts 141a-d are closed momentarily.

Thus, it will be seen, in connection with the description of the circuit diagram, that the operated groups of contacts are effective to control the energization of the recording magnets 85, when the latter are in the recording position. It is seen that the operation of the switching means just described is effected in timed relationship with the operated sheet feeding means, data printing means, and the positoning means for the recording magnets.

Operation

Referring now to Figs. 11 and 12, the operation of the machine will be described in conjunction with the circuit diagram. It is seen that an individual contact 100 of each magnet selector means is connected to an individual magnet coil 85. The magnet coils are connected in groups of fours in the individual condensers 150a, 150b, 150c, and 150d, which condensers, in turn, are connected to the normally closed contacts 140a, 140b, 140c, and 140d, respectively. The last mentioned contacts, in turn, are connected by the common conductor 151 to one terminal of a suitable power supply, such as the rectifier unit, designated by the reference character 153. The other terminal of the power supply is connected by the common conductor 152 to the common terminals of each group of magnets 85, and one terminal of each related condenser. Each elongated contact 102 of the said selector means is connected to a corresponding one of the group of normally open contacts 141a to d. Each group of four magnets 85 in Fig. 11, corresponds to the individual magnets of each vertical group or column shown in Fig. 8.

For the described conditions, it is seen that

the output circuit of the rectifier unit 153 is connected directly to the individual condensers 150a to d by means of the related switching means, namely the individual sets of normally closed contacts 140a to d, respectively, to charge the said condensers. These individual charging circuits are maintained throughout the machine cycle until approximately the 340° cycle point, at which time the described charging circuits are disconnected from the said rectifier unit, by virtue of the opening of contacts 140a to d, and individual discharging circuits are established, by virtue of the closure of the contacts 141a to d. The magnets 85 of each group are selectively connected to the individual and related discharging circuits by means of said magnet selector means. The selection of the magnets 85 of each group depends upon the settings of the annular members 108a to d and the related conducting arms 105.

Upon closure of the contacts 141a to d, the condensers 150a to d are connected to the individual discharging circuits, which circuits include certain selected magnets 85 of each group, to effect energization of the selected magnets due to the discharging of the related condensers.

In summarizing, it might be desirable to trace the operations of the main control elements described hereinabove, and the control circuits of the machine for a specific example, therefore, let us assume that the data 0.12R is set up on the manipulative instrumentalities of the keyboard control unit by depressing the corresponding data keys 20 in each of the banks or orders. Upon depression of the motor bar 23 (or operation of the crank 41) the cam shaft 24 is set into operation to cause the indicator gears 36 to be set at different positions by the described differentially settable means in accordance with the settings of the depressed data keys 20. The said gears 36 in turn cause the type segments 115a to d and the corresponding annular members 108a to d to be set or positioned accordingly to represent the selected data. The shaft 68 of the recording unit 55 is also set into operation to effect the following sequential and timed operations (1) operation of the ribbon feed mechanism, (2) cocking or setting of the print hammer arrangement during the 160° to 265° cycle points, (3) printing of the setup data (0.12R) on the record sheet 50 at the 265° cycle point, by releasing the said hammer arrangement, (4) operation of the sheet feeding mechanism during the 270° to 330° cycle points to advance the magnetizable area of the sheet to be recorded to the magnetic recording station, (5) positioning the groups of recording magnets 85 into recording position during the 250° to 335° cycle points, and maintaining the said magnets in recording position during the 335° to 345° cycle points, and (6) rendering the individual switching means operable approximately at the 340° cycle point, under control of the common control means, such as cam 143, which is operated in timed relationship with the above-mentioned elements to open the sets of contacts 140a to d and close the sets of contacts 141a to d.

In this manner, the individual condensers 150a to d are alternately connected to the rectifier unit 153 to be charged, and to the selected magnets 85 of each related group to energize these magnets by the condenser discharges.

In Fig. 11, the annular members 108a to d and the corresponding conducting arms 105 are shown in the proper positions for representing

the selected data 0.12R. Now upon closure of the said contacts 141a to d the condensers 150a to d are connected in the following discharging circuits respectively: (1) one terminal of the charged condenser 150a to contacts 141a, conducting segment 102, conducting arms 105, engaged contacts 100, related magnets 85-1 and 85-3 to the other side of condenser 150a, energizing said selected magnets to effect recording of the magnetic impressions in the first and third index point positions to represent the character R, as indicated in Fig. 13 by the shaded areas; (2) one terminal of the charged condenser 150b to contacts 141b, conducting segment 102, conducting arms 105, engaged contact 100, related magnet 85-3 to the other terminal of the said condenser 150b, energizing the selected magnet to effect recording of the magnetic impression in the third index point position to represent the character 2 as indicated in Fig. 13; (3) the terminal of the charged condenser 150c to contacts 141c, conducting segment 102, conducting arms 105, engaged contact 100, related magnet 85-4 to the other terminal of the said condenser 150c, energizing the selected magnet to effect recording of the magnetic impression in the fourth index position to represent the character 1, as indicated in Fig. 13; and (4) one terminal of the charged condenser 150d to contacts 141d, conducting segment 102, conducting arms 105, engaged contact 100, related magnet 85-1 to the other terminal of the said condenser 150d, energizing the selected magnet to effect recording of the magnetic impression in the first index point position to represent the character 0, as indicated in Fig. 13.

Immediately upon the discharging of the condensers 150a to d, the contacts 141a to d are opened and contacts 140a to d are closed to connect the said condensers to the described charging circuits, in order to charge the condensers for further recording operations. The positioned groups of magnets 85 are also returned to their non-recording positions during the 345° to 360° cycle points, so that during the following cycle of operation, the desired data can be printed on the proper line space, and the record sheet then be advanced to the magnetic recording station as described.

Thus, it is seen that discrete magnetic index points are recorded in different index point positions to represent the desired and selected data set up on the keyboard control unit. By employing the condenser discharge principle for energizing the selected magnets, as inexpensive and simplified apparatus is provided for producing the necessary magnetizing currents. Also, magnetizing forces of constant values are produced by employing this principle, which is important, in order to insure that the remanent fields of each of the magnetic index points are approximately of the same relative magnitude. Another feature residing in the present case, due to the use of the condenser discharge principle, is protection afforded to the recording magnets. The windings of these magnets necessarily must be of a limited current carrying capacity, since they must be restricted in size, due to the required close spacing thereof; and therefore, if, for some reason, the connection between the power supply and the recording magnets (contacts 141a-d) were to become fixed or stuck for a relatively long time, the recording magnets

would be subjected to the magnetizing currents possibly sufficiently to burn out their windings, if the condenser discharge principle were not employed.

- 5 While there have been shown and described and pointed out the fundamental novel features of the invention as applied to a single modification, it will be understood that various omissions and substitutions and changes in the form and 10 details of the device illustrated and in its operation may be made by those skilled in the art without departing from the spirit of the invention. It is the intention therefore to be limited only as indicated by the scope of the following 15 claims.
- What is claimed is:
1. A magnetic recording apparatus for recording coded discrete magnetic representations on a magnetizable sheet comprising a plurality of recording magnets, a common retaining block of magnetic material provided with a plurality of spaced apertures for receiving the said recording magnets, means for supporting the said block and magnets on one side of the magnetizable sheet, a common backing plate member of magnetic material, and means for supporting the backing plate member on the other side of the said sheet opposite the said recording magnets.
  2. In an apparatus for recording discrete magnetic code spots on a magnetizable sheet material, a backing member of magnetic material of high permeability and low retentivity, a supporting member adjacent thereto, a group of recording magnets mounted on said supporting member and having protruding pole pieces facing said backing member, one of said members being movable outward from the other member, to provide a gap between said pole pieces and said backing member to receive the magnetizable sheet material; means to move said movable member toward the other member to squeeze the magnetizable sheet material between said pole pieces and said backing member, and means to energize said recording magnets.
  3. In an apparatus for recording discrete magnetic code spots on a magnetizable sheet material, a backing member of magnetic material of high permeability and low retentivity, a supporting member adjacent thereto, a group of recording magnets mounted on said supporting member and having protruding pole pieces facing said backing member, one of said members being movable outward from the other member, to provide a gap between said pole pieces and said backing member to receive the magnetizable sheet material, means to feed the magnetizable sheet material intermittently through said gap, means to move said movable member toward the other member to squeeze the magnetizable sheet material between said pole pieces and said backing member, means to energize said recording magnets; and means to operate said feeding means, said moving means, and said energizing means in timed relation, so that said recording 40 means is energized while said magnetizable sheet material is squeezed between said pole pieces and said backing member and during intermissions in the operation of said feeding means.
  4. Apparatus as described in claim 2, wherein 45 selective control means are provided to select one or more of said recording magnets for simultaneous operation by said energizing means.

JAMES W. BRYCE.
